YARN-WINDING MACHINERY

William Harry Kimpton, Wilmslow, England, assignor to Celanese Corporation of America, a corporation of Delaware

Application October 3, 1946, Serial No. 700,985
In Great Britain October 8, 1945

5 Claims. (Cl. 242—32)

1

This invention relates to yarn-winding machinery and particularly to pirn-winding machinery, and is especially concerned with an automatic pirn-winding machine of the kind described in U. S. Patent No. 2,306,268 of December 22, 1942, in which, when a pirn has been completed, it is automatically removed from the winding position and replaced by an empty pirn tube on which the winding of the fresh pirn proceeds.

The machine described in U. S. Patent No. 2,306,268 of December 22, 1942, is a spindleless machine, in which the pirn tube instead of being mounted on a long spindle passing through its axis, is gripped between two centres engaging with the ends of the tube, one of said centres being driven so as to rotate the tube. When the winding of a pirn is completed, the other centre is moved axially so as to release the completed pirn and allow it to drop away from the winding position and, before the centre so moved is returned, a fresh pirn tube is lifted by means of a pair of swinging arms into a position in alignment with the centres so as to be gripped on the return of the moving centre. This machine is adapted for the winding of pirns on pirn tubes of a particular length, but it has now been found that the machine can be modified so as to wind pirns of any length within a substantial range.

According to one feature of the present invention, therefore, an automatic spindleless pirn-winding machine adapted for the winding of pirns of different lengths comprises an inner centre, an outer centre adjustable relatively thereto and adapted in co-operation therewith to grip a pirn tube, two tube-feeder or lifter members adapted to transfer a pirn tube from a magazine into alignment between the centres, one of said members being adjustable in accordance with the position of said adjustable centre, and magazine means adaptable for pirns of any length, for accommodating a series of empty pirn tubes of which the end tube is within the range of action of said lifter members. By these means the machine can be adapted to wind pirns of any length within a substantial range, and to accommodate the pirn tubes on which such pirns are to be wound.

A convenient arrangement for lifting a fresh pirn tube into alignment with the centres comprises a horizontal shaft (i. e. parallel to the axis of the pirn being wound) carrying a pair of depending levers, the lower ends or feet of which are adapted to engage the lowest pirn tube in a magazine containing a series of such tubes

2

one above the other. The feet are shaped so as to lift the lowest pirn tube out of the magazine and into alignment with the centres and, when the tube has been gripped by the centres, to withdraw and leave the pirn tube in the winding position. Since the shaping of the feet so as to leave the pirn tube in this position is apt to give insufficient control over the lowest tube in the magazine in the idle position of the arms, i. e. during the winding of a pirn, it is a further feature of the invention to provide movable claws mounted on the feet of the lifter arms and adapted, in the idle position of such arms partly to embrace the lowest pirn tube in the magazine and prevent its dislodgment. When the lifter arms are raised, however, the claws swing downwards thereon and allow the transfer of the pirn tube to the centres without interference.

20 10 One of the lifter arms engages an empty pirn tube near the base thereof, and this arm is fixed on the horizontal shaft by which the arms are actuated. The outer arm is arranged so that it can be adjusted along the length of the shaft, to correspond in position with the outer centre when the latter is adjusted in order to adapt the machine for the winding of a different length of pirn. The actuation of the shaft is conveniently effected at a position thereon between the two arms and out of range of the movement of the outer or adjustable arm.

25 It is necessary that the traversing and chasing mechanism of the machine should be such as to give a potential traverse, i. e. the steady movement along substantially the whole length of the pirn, over a distance sufficient for the building of the longest pirn in the range to be handled, the outer end of such potential traverse distance being unused when pirns of less than the maximum length are wound. It is also necessary, in order to wind pirns of different lengths, that the period of winding at the end of which the pirn is released and a fresh pirn tube supplied, should be adjustable. Such adjustment, however, is normally provided in pirn-winding machines, whether automatic or not, in order to adapt them for the winding of yarns of different thicknesses.

30 35 The adjustment of the outer centre may be effected by any convenient means conforming with the means employed for moving the centre in order to release a completed pirn. It is preferable that the latter movement should be effected by mounting the centre on the end of a pivoted arm lying generally at right angles to the axis

of the purn being wound. In this case the position of the inner centre may be adjusted by adjusting the pivot of the lever which carries it, the lever being connected to its actuating means by a chain or link that is replaceable by one of different length when the length of purn is to be changed. Alternatively, where an outer centre is mounted on a spring-loaded plunger as described in U. S. Patent No. 2,306,268 the plunger may be carried on a vertical pillar, the base of which is secured in a slide along which it can be adjusted. The former means are generally preferable as economising in space at the front of the machine and enabling the maximum length of purn to be increased without increasing the space occupied by the machine.

The automatic doffing and donning mechanism as modified in accordance with the present invention can be built as a unit independent of the spindle-driving and traverse-operating mechanism and may therefore be readily applied to existing designs of non-automatic purn-winding machines, with little structural modification and without alteration of the basic method of operating the machine. Although each mechanism operates independently, it is convenient to drive a plurality of the mechanisms by common means, which enables the invention to be readily applied to the usual type of purn-winding machine having two or more spindle units on a common frame.

By way of example one form of improved automatic purn-winding machine in accordance with the invention will now be described in greater detail with reference to the accompanying drawings. The machine described is, like that described in U. S. Patent No. 2,306,268 a modification of a "spindle" type Universal No. 90 purn-winding machine. In the drawings:

Fig. 1 is a side elevation of the purn tube doffing and donning mechanism.

Fig. 2 is a plan view of the mechanism shown in Fig. 1.

Fig. 3 is a rear end elevation of the mechanism, i. e., as viewed from the standard gear box.

Figs. 4 and 5 are details of the cam-shaft clutch mechanism.

Fig. 6 is a sectional view showing the cam-shaft starting and stopping mechanism and the purn release mechanism.

Fig. 7 is a sectional detail of the purn tube lifting mechanism.

Fig. 8 shows the yarn guide resetting mechanism, and.

Fig. 9 is a side elevation of the cam shaft of the machine showing the cams and the clutch elements thereon.

Referring to Figs. 1 and 2, 1 is the gear box of a Universal No. 90 purn-winding machine, which is usually arranged to drive two spindles side by side though only one is shown. The box 1 contains two clutches in association with each spindle, one for driving the spindle itself and the other for actuating the traverse mechanism. As the use made, for the purposes of the present invention, of the mechanism within the gear box does not involve any modification of said mechanisms, it is not necessary to describe the internal arrangements of the box. It is desirable however to describe briefly the main external elements of the purn-winding mechanism to which the invention is applied.

In the "spindle" type of machine the spindle emerges from the box 1 at 2, and is of sufficient length to penetrate through the purn tube. For the purposes of the present invention however the

spindle is cut off and is represented only by a blunt point or driving centre 3 emerging from a collar 4 which is faced with rubber to provide a driving connection with the base of a purn tube. 5 The other end or tip of the purn tube enters, and is supported by a rotary cup 5 mounted in an outer bearing 6.

Parallel to the position of the purn-tube between the centre 3 and the cup 5 is a traverse bar 7 operated from within the box 1 to execute a short to and fro traverse motion along the length of the purn to be wound. The side of the bar 7 adjacent to the purn position is threaded, as shown at 8 in Fig. 2, the other half of the bar being plain as shown at 9 in Fig. 2. A feeler disc 10 is carried on the bar, the bore of the boss 11 of the disc being screw-threaded to correspond with the threads 10 but being enlarged so that the boss and disc can be pressed to one side (towards the purn) so as to be freed from the threads 8. During winding, the thread is built up on the nose of the purn and from time to time, as the bar 7 is traversed, driving contact is established between the disc 10 and the yarn on the purn. In consequence the disc is rotated slightly on the rod 7 and is driven slightly along the rod. In this way, the thread guide 12 which is mounted on a carriage 13 and connected thereby to the disc 10 is gradually carried towards the tip of the purn tube as the winding of the purn proceeds. When the purn has reached a predetermined length the normal stop mechanism provided within the box 1 operates to release a starting and stopping lever 15 by means of which the two clutches within the box are disengaged to stop the rotation of the point 3 and collar 4 and the operation of the traverse rod 7.

The winding and traverse arrangements described above are normal (except for the cutting off of the spindle) and once winding has been started on a purn tube will affect the completion of the purn in a normal manner. The modification of the mechanism in which the present invention resides relates to the arrangements by which the machine is made adjustable to deal with purns of different lengths and to the automatic carrying out of the operations of replacing the completed purn by an empty purn tube and restarting of the machine for the winding of a fresh purn. These operations are effected, after the spindle and the traverse mechanism have been stopped, by the rotation through a single revolution of a cam-shaft 16 carrying a number of cams.

55 The cam shaft 16 which, with the cams thereon and the elements of the clutch by which it is driven is shown in side elevation in Fig. 9, is carried in bearings in a lug 17 and an end plate 18 projecting downwards beneath a plate or bracket 19 secured to the lower part of the front of the gear box 1 and lying beneath the position occupied by a purn during winding. The plate 19 carries not only the cam shaft 16 and the various cams mounted thereon, but also the mechanism operated by said cams for replacing the completed purn by an empty purn tube and restarting the winding operation. The cam shaft 16 is mounted in horizontally slotted bearings in which it is retained by removable blocks 20 (Figs. 1 and 7), the various levers co-operating with the cams on the shaft being so arranged that the shaft can be readily removed without disturbing the levers.

Beneath the cam shaft 16 and at right angles thereto is a driving shaft 21 arranged to serve a

series of spindles, say 10 or 20 in number. Beneath each spindle the shaft 21 carries a worm 22 engaging with a worm gear 23 freely mounted on the cam shaft 16. A clutch between the worm gear 23 and the cam shaft enables a connection to be made between the constantly running shaft 21 and the cam shaft 16 when the winding of a pirn is completed.

The clutch is of the type described in U. S. Patent No. 2,176,970 of October 24, 1939, and is shown in the engaged and disengaged positions respectively in Figs. 4 and 5. The clutch is engaged by the motion of the starter handle 15, the free end of which is turned downward through a right angle as shown in Fig. 2 and is connected by means of an adjustable link 24 to a lever 25 (Figs. 3 and 6) mounted beneath the bracket 19. The other end of the lever 25 carries a pin 26 (Fig. 6) engaging beneath a lever 27 secured to a shaft 28 carried in bearings beneath the edge of the plate 19. The shaft 28 carries a further lever 29 by means of which the cam-shaft clutch is normally held out of engagement. On the completion of a pirn however the starting handle 15 and link 24 rise so that the pin 26 and lever 27 fall and the free end of the lever 29 moves away from the cam shaft 16.

The clutch, as shown in Figs. 4 and 5, comprises a disc 30 secured to the worm gear 23 and provided with four semi-circular notches equally spaced around its periphery. Close to the disc 30 is a disc 32 secured to the cam shaft 16, the disc 32 having pivoted to the face thereof adjacent to the disc 30, a substantially tangential lever 33 and a substantially radial lever 34. The free end of the lever 33 projects sideways across the periphery of the disc 30 and is shaped to fit the notches 31. The lever 33 however is spring-loaded outwards so that the end of the lever tends to disengage from the periphery of the disc 30. The lever 34 extends past the lever 33 and its free end is bent over so as to engage the outer side of the lever 33 which is shaped so that as the end of the lever 34 moves towards the end of the lever 33 it forces the lever 33 inwards against the periphery of the disc 30. The lever 34 is loaded by means of a spring 35 strong enough to overcome the spring loading of the lever 33. During the winding of a pirn, however, the lever 29 engages the lever 34 and prevents it from forcing the lever 33 against the edge of the disc 30. When the lever 29 is swung away from the shaft 16 on the completion of a pirn, the lever 34 engages and urges inwards the lever 33 so that, in the rotation of the disc 30, the next notch in the periphery thereof is engaged by the end of the lever 33 so connecting the disc 30 to the disc 32. In this way the cam shaft 16 is set in motion.

The first effect of the rotation of the shaft 16 is to permit the discharge of the completed pirn. This is done (Figs. 1, 2 and 6) by moving outwards the outer bearing 6 and the cup 5 by means of which the pirn is pressed against the spindle point 3. The outer bearing 6 is carried on the upper end of a lever 37 which is loaded inwards by means of a spring 38 (Fig. 6) to enable the cup 5 to hold the pirn tube against the spindle point 3. The lever 37 is connected by means of a chain 39 to the upper end of a lever 40 pivoted at 41 on the end plate 18 beneath the bracket 19. The lever 40 carries a cam follower 42 engaged by a cam 43 on the cam shaft 16, by means of which the lever 40 and thereby also the lever 37 are withdrawn to release the complete pirn. The lever 37 is pivoted at 100 in a slot 101 along which the pivot 100 may be adjusted by means of a nut 102.

In this way the position of the outer bearing 6 can be adjusted to take pirns of any length allowed within the range of the length of the slot 101. At the same time the chain 39 is shortened or lengthened to suit the new position of the pivot 100. A plate 103 (Figs. 2, 3 and 6), moving with the pivot 100, is provided to which the lower end of the spring 38 is fixed.

The cam 43 is a dual purpose cam, having a shaped projection 44 (Figs. 1, 6 and 9) on the face thereof for engaging the cam follower 42 and a projection 45 on the edge thereof (Fig. 6) for engaging a cam follower 46 carried by the lever 25 for a purpose to be described hereafter. The completed pirn released by the retraction of the cup 5 in a manner described drops through a hole 47 in the plate 19 and is received and guided away by means of a chute 48 (Fig. 1).

As the completed pirn drops through the hole 47 the yarn being wound thereon extends from the nose of the pirn to the yarn guide 12. It is necessary that this portion of the yarn should be cut and that the end still attached to the source of supply should be secured to the next pirn for winding to continue. At the same time the yarn guide 12 must be returned to the neighbourhood of the driving centre 3 so as to begin the winding of the next pirn at the base thereof. This is done by means of a lever 50 the upper end of which engages with a small bell-crank lever 51 on the yarn guide carriage 13 (Figs. 1 and 2), the bell-crank lever being connected by a rod 49 to the boss 11 of the feeler disc 10. The lever 50 is swung counterclockwise as viewed in Figs. 1 and 8 by means of a cam 52 on the cam shaft 16. The cam 52 engages with a cam feeler 53 on the end of a lever 54 secured to a shaft 55 the other end of which carries a gear segment 56. The gear segment 56 engages with a gear segment 57 secured to the lever 50, a pin and slot connection 58 being provided to enable the final position of the lever 50 to be accurately adjusted. As the lever 50 is swung over by the cam 52, the upper end of the lever 50 engages the bell-crank lever 51 which disengages the feeler wheel 10 from the screw threads 8 on the traverse rod 7, after which the continued movement of the lever 50 pushes the thread guide carriage 13 to its starting position close to the driving centre 3.

In order that the lever 50 may deal with pirns of different lengths its maximum range of movement is made sufficient to deal with the longest pirn. When shorter pirns are wound, the first part of the movement of the lever 50 is idle. In order to give the end of the lever 50 a substantial linear motion without unduly increasing its angular motion, the lever is pivoted well below the cam shaft 16, the gear segments 56, 57 reaching downwards from the level of the shaft 16 to the pivot of the lever.

At the same time as the lever 50 returns the yarn guide 12, the length of thread extending from the completed pirn to the guide 12 is engaged by a light lever 60 the end of which is bent horizontally at 61 so as to ensure the proper engagement of the thread. The lever 60 is secured to a triangular plate 62 mounted on a spindle 63, the plate being slotted at 64 to receive a pin 65 projecting from the end of a lever 66 secured to the shaft 55. Thus as the lever 50 is swung over by the rotation of the shaft 55 it takes with it the light lever 60. The end 61 of the lever 60 brings the thread extending from the thread guide 12 to a point immediately

below the driving centre 3 so that the thread crosses the rubber-faced collar 4, and is ready to be severed so as to release from the source of the supply of yarn the pирн which has just been wound.

Severing of the thread is effected (Figs. 1, 2 and 3) by means of a sickle-shaped knife 68 mounted on a vertical shaft 69 so as to be movable in a horizontal plane below the level of the driving centre 3. In its motion the knife 68 passes between two spring plates 70, 71. The lower plate 70 is sharpened so as to co-operate with the knife 68 in severing the thread, thus releasing from the source of supply of thread the pирн just wound, while the upper plate 71 is rounded off so that the end of the thread is nipped between the knife 68 and the upper plate 71 and is held across the face of the driving centre 3. The motion of the knife 68 is effected by means of a disc 72 carried on the lower end of the shaft 69 beneath the plate 19. The disc 72 is connected by means of two metal bands 73 to a further disc 74 (Figs. 2 and 3) from the edge of which projects an arm 75 connected by a powerful spring 76 to a point beneath the plate 19. A pin 77 projecting downwards from the arm 75 engages with the working edge of an end cam 78 carried on the shaft 16. No adjustment of the gripping and cutting arrangements is necessary for winding pирns of different lengths.

The completed pирн having been released by the retraction of the cup 5 and cut from the source of supply of yarn, and the cut end from the source of supply having been gripped between the knife 68 and the upper plate 71, an empty pирн is next positioned between the driving centre 3 and the cup 5. As shown in Figs. 1, 2, 3 and 7, two upstanding pillars 79, 80 on the plate 19 carry between them a magazine 81 for containing a series of empty pирн tubes. Fixed to the back of the magazine 81 are a pair of spring strips 82 which extend downwards towards the bottom of the magazine and then turn substantially at right angles so as to enter the magazine for the purpose of supporting the series of pирн tubes during the delivery of a new pирн tube to the winding position. The magazine 81 is designed for a particular length of pирн tube, and when pирns of different lengths are wound, a new magazine of appropriate size is substituted between the pillars 79, 80. The spring strips 82 may be removed from the old magazine and replaced on the new one.

Mounted on bearings 83 on the two pillars 79, 80 is a horizontal shaft 84 extending behind the magazine 81 and carrying a pair of depending levers 85, 86. The levers 85, 86 are disposed outside the limits of the magazine 81, between the ends thereof and the pillars 79, 80. The lower ends of the levers are cranked inwards beneath the magazine as shown at 87 in Fig. 1, and carry shaped feet 88, 89 within the magazine to receive the lowest pирн tube in the series carried by the magazine. The lever 85 is permanently fixed to the shaft 84, in the neighbourhood or line of the inner or driving centre 3. The lever 86, however, is adjustable along the shaft 84 in accordance with the size of the magazine 81, and the length of the pирн being wound, the set-screw 86' which holds the lever 86 in fixed relation to the shaft 84 being released for this purpose.

The lowest tube is maintained in the magazine 81 by means of a pair of claws 90 (Figs. 3 and 7) pivoted at 91 near the ends of the feet 88, 89 and resting on the plate 19. The tips of the claws 90

extend upwards so that they partly embrace the last pирн in the magazine and prevent it from being dislodged. The levers 85, 86 are swung forward, so as to position the pирн carried by the feet 88, 89 thereof between the centres 3, 5, by means of a chain 92 which is secured at its upper end to a sector 93 carried by the shaft 84 and at its lower end (Fig. 7) to a lever 95 mounted beneath the plate 19. The sector 93 is clear of the innermost position of the lever 86, occupied by the lever 85 when winding on the shortest pирн tubes that the centers 3, 6 are capable of accommodating, so that the sector 93 does not impede the adjustment of the lever 86. The lever 95 carries a cam follower 96 which engages an edge cam 97 on the shaft 16 (Fig. 7). As the feet 88, 89 are swung forward and upwards to bring the new pирн tube into position, the claws 90 swing downwards as shown in Fig. 7. At the same time the springs 82, the lower ends of which are engaged by the heads of the screws 91 on which the claws 90 are pivoted, swing forward so as to support the empty pирн tubes remaining in the magazine. When the feet 88, 89 have positioned the empty pирн tube between the centre 3 and the cup 5, the cam 43 allows the lever 46 and the lever 27 to return to winding position so that the outer bearing 6 and the cup 5 engage the tip of the empty pирн tube and nip the base of the pирн tube against the rubber facing of the driving centre 3. After this the levers 85, 86 swing back into the magazine, pushing back the springs 82 and allowing the remaining empty pирн tubes to drop so that a new pирн tube is engaged by the feet 88, 89 and claws 90. At about the same time the end cam 78 acts on the pin 77 so as to withdraw the knife 68 and release the end of the yarn, which is now secured between the base of the pирн tube and the rubber pad of the driving centre 3. The projection 45 on the edge of the cam 43 now acts on the cam follower 46 so as to swing the lever 25 upwards and, through the link 24, to move the starting handle 15 to starting position. Winding of the new pирн then proceeds.

The cycle of operations effected by the rotation of the cam shaft 16 may be briefly summarized as follows. The cycle is initiated by completion of the winding of a pирн, at which stage the normal mechanism of the gear box 1 stops the rotation of the driving center 3 and causes the free end of the starter handle 15 to rise. This, through the lever 25 (Fig. 6) causes the pin 26 to drop and allows the shaft 28 and lever 29 to rotate. This allows the clutch connecting the cam shaft 16 to the worm 22 to engage and sets the shaft 16 in rotation. The projection 44 on the cam 43 acts through the levers 37, 40 to withdraw the outer center 6, allowing the completed pирн to drop into the chute 48. The cam 52 then swings the lever 50 and the lever 60 towards the driving center 3 returning the traverse guide 12 to the starting position and causing the yarn passing through the traverse guide to enter between the knife blade 68 and the cooperating plates 70, 71. The cam 78 then swings the blade 68 into engagement with the plates 70, 71 cutting the thread beneath plate 70 so as to release the completed pирн and gripping the other end of the thread against plate 71. The cam 52 then allows the levers 50, 60 to return, and the cam 95 causes the levers 85, 86 to swing upwards, bringing a fresh pирн tube from the magazine 81 into alignment between the centers 3, 6. The cam 43 then releases the center 6 and allows the new pирн to be gripped between the cup 5 and the center 3.

This secures the thread end held by the knife 68 and plate 71 between the base of the new pirl tube and the rubber-faced collar 4. The cam 95 then allows the levers 85, 86 to return, and the cam 78 allows the knife 68 to swing out of engagement with the plates 70, 71. The projection 45 on the cam 43 then raises the cam follower 46, lifting the pin 26 and, through the lever 25, pulling down the starting handle 15. The pulling down of the starting handle 15 restarts the rotation of the driving center 3 while the lifting of the pin 26 causes the lever 29 to drop and disengages the clutch driving the cam shaft 16. Winding of the fresh pirl then proceeds, and when winding is complete the cycle is repeated.

Having described my invention, what I desire to secure by Letters Patent is:

1. An automatic spindless pirl-winding machine comprising an inner driving center, an outer center, a lever extending substantially at right-angles to the line joining said centers for carrying said outer center, means for swinging said lever toward said inner center to enable said centers to co-operate to grip a pirl tube, said lever having a pivot adjustable in position in a direction parallel to said line for the gripping of tubes of different lengths, and pirl tube storing and supply means for supplying pirl tubes in line between said centers.

2. An automatic spindless pirl-winding machine comprising an inner driving center, an outer center, a lever extending substantially at right-angles to the line joining the said centers for carrying said outer center, means for swinging said lever towards said inner center to enable said centers to cooperate to grip a pirl tube, means for adjusting the position of the pivot of said lever to enable said centers to grip tubes of different lengths, a shaft extending parallel to said line, a pirl tube magazine, a pair of depending levers on said shaft, and shaped feet on said levers adapted to swing from a position beneath said magazine upwards into alignment with said centers and to lift and transfer the lowermost tube in said magazine, the depending lever nearest said outer center being adjustable along said shaft in accordance with the position of said outer center.

3. An automatic spindless pirl winding machine comprising an inner driving center, an outer center that is movable towards said inner center so as to cooperate therewith to grip a pirl tube, a shaft extending parallel to the line joining said centers, a magazine adapted to hold a series of pirl tubes, a pair of depending levers on said shaft, shaped feet on said levers adapted to swing from a position beneath said magazine upwards into alignment with said centers and to lift and transfer the lowermost tube in said magazine, and a claw pivotally mounted on each of said shaped feet and adapted to cooperate therewith in the idle position of said feet to retain the lowermost tube in the magazine and to swing clear of the tube during the transfer thereof.

4. An automatic spindless pirl-winding machine comprising an inner driving center, an outer center that is movable towards said inner center so as to cooperate therewith to grip a pirl tube, an arm extending substantially at right-

angles to the line joining said centers for carrying said outer center, said arm being adjustable in a direction parallel to said line to accommodate pirl tubes of different lengths, a shaft extending parallel to said line, a pirl tube magazine, a pair of depending levers on said shaft, shaped feet on said levers adapted to swing from a position beneath said magazine upwards into alignment with said centers and to lift and transfer the lowermost tube in the magazine, the depending lever nearest said outer center being adjustable in accordance with the position of said outer center, and a claw pivotally mounted on each of said shaped feet and adapted to cooperate therewith in the idle position of said feet to retain the lowermost tube in the magazine and to swing clear of the tube during the transfer thereof.

5. An automatic spindless pirl-winding machine comprising an inner driving center, an outer center, a lever extending substantially at right-angles to the line joining said centers for carrying said outer center, the said outer center being adapted by swinging of said lever towards said inner center, to cooperate with said inner center to grip a pirl tube, means for adjusting the position of the pivot of said lever by discrete steps to enable said centers to grip tubes of different lengths, two shafts extending parallel to said line, a pirl tube magazine, a pair of depending levers on one of said shafts having shaped feed adapted to swing from a position beneath said magazine upwards into alignment with said centers and to lift and transfer the lowermost tube in said magazine, a claw pivotally mounted on each of said shaped feet and adapted to cooperate therewith in the idle position of the feet to retain the lowermost tube in the magazine and to swing clear of said tube during the transfer thereof, means for rotating the other of said shafts through a single revolution on completion of a pirl, cams on said other shaft adapted to swing the lever carrying said outer center so as to release the completed pirl, to actuate said depending levers, and to restart winding on a fresh pirl tube transferred thereby, a thread-guide return lever adapted to shift a thread-guide from the neighborhood of the outer center to the neighborhood of the inner center, said return lever being pivoted substantially below said other shaft, a further cam on said other shaft for actuating said return lever, and downwardly extending connecting means between said cam and said return lever.

WILLIAM HARRY KIMPTON.
